CIRCUIT BREAKER

Toshi Asanuma, Toshima-ku, Tokyo, Japan

Application March 1, 1935, Serial No. 8,963. Renewed January 5, 1939. In Japan March 2, 1934.

7 Claims. (Cl. 200—150)

This invention relates to improvements in electric oil switches of high tension, the object being to provide a switch making easy and safe the handling of high power.

5 The invention relates to improvements in electric circuit breakers for use with circuits of high tension, and is directed more particularly to circuit breakers of the oil-blast type, in which blasts made by pump or other pressure are directed 10 across the electric arcs, with the pressure of the blast of oil continually increasing during the circuit interrupting action.

The invention contemplates the use of oil under pressure for breaking the contact and creating 15 oppositely directed passages for the flow of oil under pressure which forces the arc incident to the contact break across the edges of fixed plates, together with mechanical switch-closing means which is tensioned for switch-closing operation 20 in the breaking of the circuit and released at will for the switch-closing function.

The accompanying drawings being illustration of the invention:

Figure 1 is a view in vertical section, partly in 25 elevation, of the improved circuit breaker, the contacts being shown closed.

Figure 2 is a similar view, the contacts being shown in their positions occupied in the initial separation of such contacts.

30 Figure 3 is a sectional detail, partly in elevation, of the means for supporting the pump cylinder at the required height.

Figure 4 is a view similar to Figure 2, showing the contacts separated to their maximum extent.

35 Figure 5 is a top plan view of the circuit breaker.

Figure 6 is a section on line A—A of Figure 4.

Figure 7 is a section on line B—B of Figure 4.

The improved circuit breaker comprises a bowl-like lower section 1, an intermediate section 24 40 removably secured upon the upper end of the lower section, and a casing 21 secured upon the upper end of the intermediate section. The fixed contacts are housed within the lower body section 1, the movable contacts are guided in the intermediate section 24, and the operating means for the movable contacts is mounted in the upper or casing section 21.

The body section 1, open at the upper and lower 50 portions, is provided with a bottom plate 11 threaded into the lower opening and centrally formed with an upstanding ledge defining a central opening in said bottom plate. Supported upon an outer shoulder in said ledge is an annular support 12 within which are secured tubes

10 which depend through the opening in the bottom plate 11 and within each of which tubes there is arranged a terminal of the conductor leads controlled by the switch.

Mounted upon the support 12 and connected to the upper ends of the tubes 10 is a circular disk 13 having an upstanding flange, the inner surface of which is slightly convergent downwardly. The conductor terminals, indicated at 10', are threaded into elements 13' which rest 10 upon the upper surface of the disk 13 on opposite sides of an upstanding partition 3' carried by said support.

Mounted in the elements 13' are the respective fixed contacts constituting oval-shaped bodies 3 15 in each of which are arranged three movable elements including circular heads 4, screen-like depending bodies 6 and springs 7 maintaining the heads 4 normally in positions slightly above the pole-pieces 3, the movement of the heads 20 being limited by stops 5.

The lower ends 8 of the pole-pieces 3 are of course in electrical contact with the extensions of the conductor terminals 10', and as the movable elements 4 of the pole-pieces of contacts 25 permit convenient renewal without the necessity of renewing the entire pole-piece and reduces the area of actual contact under separation of the contacts to reduce the arc.

A tubular director 14, which is of insulating 30 material, is formed to encircle the pole-pieces of fixed contacts, the lower end of this director being frictionally held against the inner surface of the upstanding flange of the disk 13 and the upper surface of the director terminating on a 35 plane materially above that of the fixed contacts in an annular ring 14', the margin of the interior opening of which is in line with the outer margin of the fixed contacts.

Below the upper annular ring, the director is 40 formed with diametrically opposed openings 15, the lower margins of which are in the plane of the fixed contacts, and within these openings are supported cutting blades 16 of rigid insulating material. The blades 16 are materially less in 45 thickness than the vertical dimension of the openings 15, so that the openings 15 provide a space above and below each plate or blade. The blades 16 extend outwardly beyond the margin of the director 14 and their inner edges conform 50 to the shape of that of the fixed contacts 3, as clearly shown in Figure 7.

The partition 3' extends upwardly to the lower margin of the interior opening in the director ring 14', so that this partition extends above 55

the cutting blades 16, as will be clear from Figures 1, 2 and 4.

An insulating lining 17 is supported at its upper end upon an outstanding ledge at the upper end of the body 1, the arrangement being such that the lining depends within the body to provide a narrow space 18 between the body and lining. The lower end of the lining is open to provide communication from the space 2 within the lining and within which the fixed contacts and connecting parts are mounted and the space 18 between the lining and body. The space 18 is of restricted cross-sectional area and is provided to define a lengthy path for the downward flow of the oil and a restriction in the speed of that flow.

The lining 17 is interiorly thickened at the upper end to provide a wall having a central opening to receive and support a thimble 19 in axial alignment with the director 14, with such wall reduced to provide with the intermediate member 24 a chamber 21 which, through the medium of a passage 20 passing through the thickened wall of the lining, is in communication with the annular space 18 between the lining 17 and body 1.

The intermediate section 24 is bolted to the body 1 to form an upper wall for the chamber 21, with the upstanding outer wall of such intermediate section formed with an annular channel 22 closed at the upper end and open at the lower end to the chamber 21. Thus, the annular space 22 is in open communication with the space 2 of the lining 17 in which the fixed contacts are mounted through the medium of the chamber 21, passage 20 and space 18.

The space 22 is formed with relief openings closed by plugs 23 set at various heights of the space 22, whereby, in filling the circuit breaker, the height of the oil in the space 22 may be determined by dislodging the appropriate plug 23 and wherein, after the reinsertion of the plug, the air is trapped in the space 22 above the level of the oil for a purpose which will later appear.

The bottom of the intermediate member is centrally formed with a guide sleeve 25 which extends above and below the bottom which is coaxial with the director 14, that portion of the guide sleeve below the bottom interfitting with the thimble 19 to form an inner wall of the chamber 21 and at the same time a non-leaking connection with the thimble. A sleeve valve 43 is movably mounted in the guide sleeve 25, the upper end of the guide sleeve being formed with an annular recess to receive a projection on the upper end of the sleeve valve to limit the upper and lower movements of the sleeve valve relative to the guide sleeve.

The guide sleeve 25 is formed with a series of vertically extending inwardly projecting spaced ribs defining between them a series of passages which are fully open at the upper ends and which, at their lower ends, communicate through ports 42 with the interior space 2 when the sleeve valve is at its lower limit, as indicated in Figure 1 of the drawings. An annular rib closes the lower ends of these oil spaces against direct flow downwardly.

Slidably fitted within the sleeve valve and contacting with the inner edges of the ribs of the sleeve valve is a pump cylinder 38 formed at its lower end as an annular ring and above such ring as spaced concentric walls, the outer one 38' of which is longer than the inner one 38". An insulating ring 39 and contact ring 40 are

secured to the ring portion at the lower end of the cylinder 38, the contact ring 40 being connected to the lower edge of the insulating ring 39 and the latter connected to the lower edge of the ring portion of the cylinder, with both the insulating ring 39 and the contact ring 40 of the same externally and internally dimensioned proportions as and aligned with the pump cylinder 38.

The outer surface of the outer wall 38' of the pump cylinder is provided at the upper end with an annular rib 46 and at a point below the upper end with a second annular rib 45, the upper rib 46 serving as a means to locate the position of the pump cylinder through mechanism to be later described, while the lower rib 45 is so positioned that in the downward movement of the pump cylinder, such rib 45 will engage and depress the sleeve valve 43.

The open upper end of the upper casing 27 is provided with a pressure cylinder 32 which is of less diameter than the casing 27 and provided with an annular outstanding flange to provide for securing and centering the pressure cylinder in place. The lower end of the pressure cylinder is formed with an inwardly depressed pocket 31 open to the interior of the cylinder and connected by a pipe 30 leading through the wall of the casing 27, with the pocket providing a trap for water and lubricant leaking across the piston and providing for the discharge from such trap to prevent such materials entering the insulating oil in the circuit breaker.

A differential piston 35 is mounted within the pressure cylinder 32 with suitable packing, the piston being extended as a hollow body 35' which fits within the inner wall of the cylinder 38 and is provided at its lower end with a packing 37 to seal the juncture between the piston and cylinder. A spiral spring 36 underlies the projecting portion of the piston 35 and functions to force the piston upwardly and the cylinder 38, insulating ring 39 and conductor ring 40 downwardly. Under the influence of the spring, the conductor ring 40 is moved into contact with and slightly depresses the movable sections 4 and thereafter electrically engages the fixed contacts 3 to close the circuit.

In this movement of the conductor ring 40, it will be noted that it passes through the upper ring member 14' of the director 14 between the inner edges of the plate 16 and into engagement with the fixed contacts. In this position, the lower end of the conductor ring 40 beyond those portions directly engaging the contacts is supported in the opening 15 of the director wholly free of underlying contact and providing faces which, as will be later explained, may be reached by the oil under pressure and incident to such pressure be forced to move upwardly to break the contacts.

It will be noted particularly from Figure 7 that the so-called fixed contacts occupy but a portion of the circular area, leaving a space x between the ends of these contacts. This space provides an uninterrupted area which directly underlies the lower end of the conductor ring 40 and which is exposed to the pressure of the oil in the operation of the device to create an upward pressure on the conductor ring to break the contacts.

Within the casing 27 is placed an operator including a rack 49 and cooperating pinion 48. The hollow end of the rod 50 forming an extension of the rack 49 is formed with two diametrically opposed axial slits 51, each with a shoulder 53 out-

ward. Through the shoulders 53 the rack 49 hangs on a spiral spring 52 which bears on the bottom of a hole in the crown of the cylindrical body 27 and on the top of the hollow end of the rod 50 a sleeve rests slidably in the same hole by a shoulder formation at the upper end on which sleeve is mounted a spiral spring 58 stronger than the spring 52. An open-bottom spring case is screwed at its lower end into the hole in the flange 10 of press cylinder 32, compressing both the springs 52 and 58 until the outside shoulder of said sleeve comes in contact on the shoulder in the hole in the cover. Through the opening centrally bored in the crown of the spring case a hollow spindle 15 55 extends, mounted for rotation by disc head 56 but held against longitudinal movement. The lower end of spindle 55 projects into the hollow end of the rod 50 and has two stops 54 on the opposite sides immediately above the top of the 20 rod 50. Through the spindle and knob loosely extends a testing rod 57 screwed at the lower end into the rod 50, with its upper end projected a little above the disc head 56.

In a position of stops 54, as shown in Figures 1, 25 2 and 3, the rod and rack being only under the influence of the weak spring 52, may be easily moved downwardly but not upwardly, as the top of the rod is in contact with the stops 54 on the spindle 55, and thus the pinion is always turnable counterclockwise but not clockwise. In consequence, the rim 46 at the upper end of the outer wall of the pump cylinder, in the upward movement, passes above the pinion 48, but following the beginning of its downward movement the 30 pump cylinder stops, being limited by engaging with the pinion not rotatable clockwise, and thus the pump cylinder is supported in the required height. This condition may be changed at will by turning the knob 56 and bringing the stops 40 54 in line with the slits 51, allowing the spring 35 36, contracted as shown in Figure 4, to compress the spring 58, to drive up the rod and rack, and to turn the pinion clockwise. The position of the testing rod is thus an indication and shows the engagement of the cylinder with the pinion.

There are an oil inlet 33 with tap in the top and an opening 29 with tap in the side of the oil chamber 28 which communicate with the switch chamber 2 by the passages 42 and 44 provided in the lowest position of sleeve valve 43, and in the outer wall of the middle section 24 are provided a series of openings 23 bored in steps and 50 screwed taps.

Freeing one of the openings 23 and openings 55 29 and 33, through the latter, the charge of oil poured in the oil chamber 28 flowing by the passages 44 and 42 fills in the chamber 2, annular space 18 and through the openings 20, the annular space 21 and the lower portion of the annular space 22, and flows out of the open hole 23 which is then closed. The walls and surface of the under oil catching the air in the remainder of the annular space establish an air cushioning chamber which is so devised that its capacity may 60 be adjusted by freeing any one of openings 23, having an essential effect upon raising the pressure on oil to force the ring electrode 40 upwardly against the action of the spring 36. The opening 29 settles the oil level in the oil chamber 28 and 65 is closed.

The operation of the described construction is as follows:

In Figure 1, when the operating medium, for instance compressed air, has been admitted into 70 the cylinder 32, the compressed air drives the

plunger 35 inwardly, as well as the body of oil within the pump cylinder downwardly. As the free portion of the contact ring 40 is encircled by the tubular director 14, the oil is compelled to act upon the underside of said portion and to lift the cylinder 38, separating the bridging contact 40 from the fixed contacts 3 and auxiliaries 4.

In the parting of contact faces of electrodes, the communication between the interior of pump cylinder and switch chamber is established above 10 the surfaces of the poles through the openings 15, as shown in Figure 2. At the same time the powerful oil pump causes the two oppositely-directed high velocity blasts of oil across the arcs formed between the said separating contact faces, 15 and through the openings wherein the cutting blades are placed and into the chamber 2. Therefore by means of the openings, the arcs are forced on to the cutting edges of the blades and cut off by them. The extinguishing of the arc is 20 certain and practically instantaneous in every instance. In order to make the extinguishing action more efficient, the pressure of the oil blasts are continuously increased during the operation, incident to the fact that the increase of oil in 25 the chamber 2 lifts the sleeve valve 43 covering the openings 42 and cutting off the passages to the upper chamber 28. In the consequent compressing of the air in the top of the chamber 22, and raising the pressure on the oil and air, the 30 rise in pressure is proportional to the intensity of the spring 36 between the cylinder and plunger in its contraction.

Each flux of oil, carrying the arcs and bubbles peculiar to each terminal, in the same side with it, in passing across the parting contact faces, is directed against and over the rigid edges of the blades and thereby the arcs and bubbles drawn between contacts will be cut or sheared into two parts which are cooled and compressed between 35 the edges and the continually flowing oil. Thus, the arcs have been in practically every instance extinguished instantaneously and surely. But if this is not instantly effective, it takes place at the next instant, for the arcs at once will be 40 folded into W-shapes, hanging the middles on the edges and having the ends on the contact faces, by the flow of oil from both sides of the cutting blades at the edges of which the flow of oil separates and is carried away, being made 45 more slender and weaker and being beaten on the same points and so weakened on the edges by the increased oil momentum, will thus be cut off immediately after the arcs have come in contact with the edges. Until the end of stroke of plunger has been reached, the excess oil is pumped out 50 for cooling. When the under surface of the cylinder passes above the upper edges of the ungrooved portion 41 of the sleeve valve, the exit ducts 44 become uncovered, the chambers 2 and 55 28 being in communication and the oil and gases pass out through the passage from chamber 2 into the chamber 28 due to the expansion of the air hitherto compressed in the chamber 22, balancing the pressures. Gases escape by the freed opening 33 or piping 38 from the chamber 28 into 60 the air.

The pump cylinder and sleeve valve will then 65 lose their supporting forces and the sleeve valve at once drops but the pump cylinder comes to rest on the tooth of the pinion by the rim 46, while the heated oil and gases in the chamber 2 are displaced with the cold oil from the oil chamber above. The engagement may be released whenever required by turning the knob 56 and putting 70 75

off the mesh of the stops on tube 55 with the top of the rod 50.

When the pump cylinder is freed from the pinion, it is by the action of spring 36 driven into the chamber 2. This puts the oil under pressure, compressing the air into the chamber 22, at the same time closing the chamber 2 with the sleeve valve lifted and then an amount of the movement will bring the supporting pressure of the oil under the ring conductor equal to the tension of spring—the former increasing but the latter decreasing—preventing the further movement of the cylinder. But immediately after the pinion has been released, the exhaust of the cylinder is opened, allowing the same spring to drive the plunger upwards. During the movement, the plunger sucks the oil from the chamber 2 into the cylinder, forming a partial vacuum in the former. The actions of the partial vacuum as well as the spring drive the cylinder against the electric poles until the ring conductor comes in contact with them and the circuit is closed, affording a quick and non-arching closing. The vacuum in the chamber is filled through the passages 44 and 42 permitted by dropping of sleeve valve, with the oil from the chamber 28 above and vacuum in the cylinder through the openings 47 with the oil from the same. On the other hand, the plunger reaches its upper limit when exhaust is closed. Now the switch is ready for use again.

What is claimed to be new is:

1. A circuit breaker including a casing designed to contain a body of oil, a relatively fixed electrode in the casing, a relatively movable electrode in the casing, manually operable means tending to move the electrodes into circuit closing relation, means for creating pressure on the body of oil to cause the oil to move the movable electrode from circuiting contact with the fixed electrode, the movement of the movable contact tensioning the mechanical means for operating said contact toward circuit closing relation, means to hold the movable contact in that open relation following operation of the oil under pressure and against the influence of the mechanical closing means, a tubular director surrounding the electrodes and formed with diametrically opposed passages substantially in the plane of the contacts, and an arc breaking plate fixed in each of said passages and spaced from the upper and lower walls thereof.
2. A circuit breaker including a lower casing, an upper casing, a valve sleeve controlling communication between the casings, the casings being designed to contain a body of oil, a fixed electrode in the lower casing, a movable electrode moving through the upper casing into circuiting contact with the fixed electrode, means in the lower casing for creating pressure on the body of oil in the upper casing to cause the oil to lift the movable electrode and the sleeve valve to cut off communication between the upper and lower casings, means immediately above the fixed electrode for directing the oil under pressure laterally of the electrode when the movable electrode is in non-circuiting relation to thereby direct the arc laterally of the electrode, a spring for moving the movable electrode into circuiting relation with the fixed electrode, said spring being tensioned in the oil pressure movement of the movable electrode, manually controlled means for holding the movable electrode in non-circuiting position with the spring under tension, and means for causing the spring on release of the

manually controlled means to move the movable electrode toward the fixed electrode and create oil pressure in the lower chamber, the movement of the movable electrode under the influence of the spring serving to move the sleeve valve to establish communication between the chambers to relieve such pressure and permit rapid circuiting movement of the movable electrode.

3. A circuit breaker including an upper casing, a lower casing, a movable sleeve valve controlling communication between the casings, a movable electrode movable through the upper casing, a fixed cooperating electrode mounted in the lower casing, the upper and lower casings being designed to contain a body of oil, means in the lower casing for creating pressure upon the surface of the body of oil in the upper casing to subject the movable electrode to a pressure-compelling movement away from the fixed electrode, the oil under pressure flowing between the electrodes when the movable electrode is in non-contacting relation with the fixed electrode, an element encircling the fixed electrode and formed with passages to direct the oil under pressure in opposite directions laterally of the electrodes after the movable electrode is moved to a non-circuit closing relation with the fixed electrode, and a fixed element dividing each passage into upper and lower openings and itself providing an arc-breaking element, the upper and lower openings providing for the passage of oil under pressure into the lower casing.

4. A circuit breaker including an upper casing, a lower casing, a movable sleeve valve controlling communication between the casings, a movable electrode movable through the upper casing, a fixed cooperating electrode mounted in the lower casing, the upper and lower casings being designed to contain a body of oil, means in the lower casing for creating pressure upon the surface of the body of oil in the upper casing to subject the movable electrode to a pressure-compelling movement away from the fixed electrode, the oil under pressure flowing between the electrodes when the movable electrode is in non-contacting relation with the fixed electrode, an element encircling the fixed electrode and formed with passages, to direct the oil under pressure in opposite directions laterally of the electrodes after the movable electrode is moved to a non-circuit closing relation with the fixed electrode, and a fixed element dividing each passage into upper and lower openings and itself providing an arc-breaking element, the upper and lower openings providing for the passage of oil under pressure into the lower casing, mechanical means for moving the movable electrode toward circuiting relation with the fixed electrode, said means creating a pressure on the oil in the lower casing during such movement, and a by-pass in the lower casing forming a restricted lengthened channel communicating with an automatic pressure means at the top and with the lower casing at the lower end.

5. A circuit breaker including a lower casing, an upper casing, fixed electrodes in the lower casing, a movable electrode in the upper casing, said movable electrode including a pump cylinder, a sleeve valve encircling the pump cylinder and providing communication between the upper and lower casings, means on the pump cylinder to operate the sleeve valve in the circuit closing movement of the movable electrode, a spring for moving the movable electrode into circuit closing

relation with the fixed electrodes, the upper and lower casings being designed to contain a body of oil, a plunger operative within the pump cylinder for creating pressure on the oil to lift the movable electrode, a projection on the pump cylinder, manually controlled means carried by the upper casing to engage the projection and hold the movable electrode in non-circuiting relation with the fixed electrodes, and means on the pump cylinder to operate the sleeve valve to establish communication between the casings in the movement of the movable electrode under the influence of the spring.

6. A circuit breaker including a lower casing, an upper casing, fixed electrodes in the lower casing, a movable electrode in the upper casing, said movable electrode including a pump cylinder, a sleeve valve encircling the pump cylinder and providing communication between the upper and lower casings, means on the pump cylinder to operate the sleeve valve in the circuit closing movement of the movable electrode, a spring for moving the movable electrode into circuit closing relation with the fixed electrode, the upper and lower casings being designed to contain a body of oil, a plunger operative within the pump cylinder for creating pressure on the oil to lift the movable electrode, a projection on the pump cylinder, manually controlled means carried by the upper casing to engage the projection and hold the movable electrode in non-circuiting relation with the fixed electrodes, means on the pump cylinder to operate the sleeve valve to establish communication between the casings in the movement of the movable electrode under the influence of the spring, a tubular director surrounding the fixed electrodes, and means carried by the tubular

director and open to the flow of oil under pressure to break the arc in the separation of the electrodes.

7. A circuit breaker including a lower casing, an upper casing, fixed electrodes in the lower casing, a movable electrode in the upper casing, said movable electrode including a pump cylinder, a sleeve valve encircling the pump cylinder and providing communication between the upper and lower casings, means on the pump cylinder to operate the sleeve valve in the circuit closing movement of the movable electrode, a spring for moving the movable electrode into circuit closing relation with the fixed electrode, the upper and lower casings being designed to contain a body of oil, a plunger operative within the pump cylinder for creating pressure on the oil to lift the movable electrode, a projection on the pump cylinder, manually controlled means carried by the upper casing to engage the projection and hold the movable electrode in non-circuiting relation with the fixed electrodes, means on the pump cylinder to operate the sleeve valve to establish communication between the casings in the movement of the movable electrode under the influence of the spring, a tubular director surrounding the fixed electrodes, and means carried by the tubular director and open to the flow of oil under pressure to break the arc in the separation of the electrodes.
